UNITED STATES PATENT OFFICE

2,260,277

BUMPER, ESPECIALLY APPLICABLE TO
RAILWAY VEHICLES

Jean Mercier, Paris, France

Original application March 7, 1936, Serial No. 67,715. Divided and this application December 12, 1939, Serial No. 308,885. In France March 12, 1935

3 Claims. (Cl. 213—223)

My present invention relates to bumpers for railway vehicles and it has for its object to provide another embodiment of the generic invention disclosed in my application filed March 7, 1936, Ser. No. 67,715, now issued as Patent No. 2,187,625, of which the present application is a division.

Essentially the present invention provides two or more buffers, disposed on either side of the longitudinal axis of the vehicle, the buffers being rigidly connected with two or more pistons, respectively, movable in corresponding cylinders which contain, at one side of the pistons, a compressible fluid, and at the other side of the pistons an incompressible fluid, the cylinder for a piston at one side being so connected with the cylinder for a piston at the other side as to effect communication between the incompressible fluid sides of the cylinder, whereby the fluid from a cylinder at one side of the vehicle will flow to the cylinder at the other side, and vice versa, according to the respective movements of the pistons.

Other objects will in part be obvious and in part be pointed out hereinafter.

To the attainment of the above objects and ends the invention still further resides in those novel features of construction, combination and arrangement of parts, all of which will be first fully described in the following detailed description and then be particularly pointed out in the appended claims, reference being had to the accompanying drawing, in which—

Fig. 1 is a horizontal section illustrating the invention.

Fig. 2 is a diagrammatic view illustrating the working of the system according to the invention.

In the drawing, in which like numbers of reference indicate like parts in both figures, 1 and 2 represent two railway vehicles each of which has a fixed cylinder 3 located one at each side of the axes of the vehicle.

The cylinders 3 of one vehicle align, respectively, with those of the opposing vehicle.

Within each cylinder is a piston 4 whose rigid rod carries a buffer 7. Each cylinder encloses a chamber 5 containing a compressible fluid and a chamber 6 containing an incompressible liquid. The chambers 5 are at the rear sides of the pistons, while the chambers 6 are at the fore sides thereof.

Preferably, the chambers 5 of the cylinders 3 are connected by a conduit 8 which acts as an equalizing conduit and which, if desired, may be omitted without greatly affecting the operation of the device.

A conduit 8 connects the chambers 6 of the pistons and contains, also, an incompressible liquid which communicates with that in chambers 5 and 6 and constitutes therewith a shiftable rigid connection between pistons 4 and 4.

Therefore when a car is negotiating a curve, the incompressible liquid passes from one cylinder to the other through a conduit 8; one of the buffers 7 is pushed in while the other moves out the same distance, because of the suction produced by the in-moving piston on the incompressible liquid. When a sudden shock occurs and both buffers 7 are pushed in simultaneously, the piston will compress the fluid in chambers 5 and 6 (and conduit 8, if such be used), thus absorbing the shock.

To supply incompressible liquid to or to discharge it from the apparatus, I provide, on conduit 8, a tube 10 which, when not in use, is closed by suitable means.

From the foregoing description, taken in connection with the accompanying drawing, it is thought that the construction, operation and advantages of the invention will be clear to those skilled in the art.

What I claim is:

1. A bumper device of the type described, for use in connection with a vehicle and especially a railway vehicle, which comprises, in combination, at least two buffers movably carried by said vehicle on either side of the longitudinal axis thereof, two cylinders rigidly carried by said vehicle, pistons movable with a fluidtight fit inside said cylinders respectively and rigid with said buffers respectively, a passage interconnecting the respective chambers of said cylinders that are located on the outer sides of said pistons, an incompressible liquid filling the whole of these two chambers and said passage, and a compressed gas filling the two other chambers of said cylinders, respectively, said pistons being normally disposed spaced from the ends of their respective cylinders in order that the buffers can move in either direction from their normal positions in which both are in the same transverse plane.

2. A bumper device according to claim 1, further including a passage interconnecting the two last mentioned chambers.

3. A bumper device according to claim 1, further including a conduit communicating with the first mentioned passage for feeding liquid thereto.

JEAN MERCIER.
